(57) **CLAIM**

The ornamental design for a surgical stent, as shown and described.

DESCRIPTION

FIG. 1 is a top perspective view of a surgical stent showing our new design;

FIG. 2 is a front side elevational view thereof;

FIG. 3 is a rear side elevational view thereof;

FIG. 4 is a right side elevational view thereof;

FIG. 5 is a left side elevational view thereof;

FIG. 6 is a top plan view thereof; and,

FIG. 7 is a bottom plan view thereof.

It is noted that the aspects shown in broken lines do not form part of the claimed design.
